GRAPHIC RECORDER

Hugh J. Hall, Los Altos, and John O. Yeiser, Palo Alto, Calif., assignors to Varian Associates, San Carlos, Calif., a corporation of California

Application January 28, 1957, Serial No. 44,639

Term of patent 14 years

(Cl. D26—1)

F i g. 1

F i g. 2

F i g. 3

Fig. 1 is a front perspective view of a graphic recorder showing our new design;

Fig. 2 is a side elevational view, to a reduced scale, the opposite side being substantially a mirror image thereof; and

Fig. 3 is a rear elevational view thereof, to a reduced scale.

A front portion of the structure of Fig. 1 is diagonally lined to indicate transparency.

We claim:

The ornamental design for a graphic recorder, as shown and described.
